(57) **CLAIM**

We claim the ornamental design for a high-frequency coaxial connector, as shown and described.

DESCRIPTION

FIG. 1 is a front, top, left side perspective view of A high-frequency coaxial connector embodying our new design;

FIG. 2 is a rear, top, left side perspective view of thereof;

FIG. 3 is a bottom plan view thereof;

FIG. 4 is a right side elevational view thereof, the left side elevational view being a mirror image thereof;

FIG. 5 is a top plan view thereof;

FIG. 6 is a front elevational view thereof; and,

FIG. 7 is a rear elevational view thereof.
